UNITED STATES PATENT OFFICE.

ELIAS L. ELLIOTT, OF NEW YORK, N. Y.

DESIGN FOR A REFLECTOR FOR ARTIFICIAL LIGHTS.

SPECIFICATION forming part of Design No. 36,126, dated October 28, 1902.

Application filed August 28, 1902. Serial No. 121,401. Term of patent 7 years.

To all whom it may concern:

Be it known that I, ELIAS L. ELLIOTT, a citizen of the United States, residing at New York, in the county of New York and State of New York, have invented a certain new, original, and ornamental Design for a Reflector for Artificial Lights, of which the following is a specification, reference being had to the accompanying drawings, in which—

10 Figure 1 is a plan view of a reflector for lamps or other artificial lights, showing my new and ornamental design. Fig. 2 is a section taken on line xx of Fig. 1.

The design consists of a series of radial ribs or prisms a , arranged about the central collar b of the reflector and on the outer surface thereof. These ribs or prisms extend downward and outward from the collar and terminate in inclines c . Below the inclines c there are four-sided pyramidal prisms d , projecting from the outer surface of the reflector, these prisms having their sides arranged as continuations of the sides of the prisms a . Below the pyramids d , on the outer surface of the reflector, are arranged prismatic ribs e , which

are practical continuations of the ribs or prisms a or are such prisms as the prisms a would form if said ribs were continued and not interrupted by the pyramids d or by the depressions or notches f between said ribs 30 and pyramids. Each rib e terminates in a bead or scallop h at the outer and lower edge of the reflector.

The inner surface of the reflector is smooth.

The reflector is composed of glass, and the 35 ornamental design shows an iridescent or prismatic appearance to the eye of the observer when seen from different viewpoints and in different lights.

What I claim as new, and desire to secure 40 by Letters Patent, is—

The ornamental design for a reflector for artificial lights, substantially as shown and described.

In testimony whereof I affix my signature 45 in presence of two witnesses.

E. L. ELLIOTT.
